United States Patent Office.

THOMAS DOLAN, OF PHILADELPHIA, PENNSYLVANIA.

Design No. 4,957, dated May 30, 1871.

DESIGN FOR A CELLULAR FABRIC.

The Schedule referred to in these Letters Patent and making part of the same.

I, THOMAS DOLAN, of Philadelphia, county of Philadelphia, State of Pennsylvania, have invented or produced a Design for a Cellular Fabric, of which the following is a specification.

In the accompanying drawing, which forms a part of this specification—

Figure 1 represents a fabric made in accordance with my design;

Figure 2, the same, slightly modified; and

Figure 3, another modification of the fabric.

The style of fabric to which my design relates is of a cellular character—that is, the fabric has rows of deep depressions or cells formed between ridges crossing each other at right angles; thus, in fig. 1—

a a a represent rows of square cells, each cell being bounded on two opposite sides by ribs, *b b*, and on the other two sides by ribs *d d*.

These ribs *d d* I make, either wholly or partially, of threads of a character differing from that of the threads of other portions of the fabric; thus, in fig. 1 these ribs are made of satin threads, which appear on the surface at intervals and impart to the fabric a brilliant appearance.

In fig. 2 black threads form part of the ribs *d*, and these threads appear on the surface in the form of spots, as shown.

In fig. 3, the ribs *d* are composed partly of black and partly of satin threads, both of which appear alternately on the surface.

In like manner threads of different material or different colors may be used for these ribs for imparting an attractive appearance to the surface of the fabric, the same general design being preserved throughout.

The distinctive feature of my design is the rows of threads which appear upon the edges of the parallel ribs, the said threads being of a different color or material from that of the body of the fabric, thus imparting a striped appearance to the latter.

Irrespective of the color or character of the threads employed,

I claim—

The design for a cellular fabric, substantially as described, and as illustrated in and by the accompanying drawing.

In testimony whereof I have signed my name to this specification in the presence of two subscribing witnesses.

THOMAS DOLAN.
